TRAY FOR DISPLAYING COIN HOLDERS OR THE LIKE

Giorgio I. Spadaro, Evanston, Ill., assignor to
Simon L. Friedman, Chicago, Ill.

Filed Dec. 10, 1962, Ser. No. 72,779

Term of patent 14 years

(Cl. D58—12.6)

FIG. 1 is a perspective view of a tray for displaying coin holders or the like, which embodies my improved design;

FIG. 2 is a top plan view of the same;

FIG. 3 is a side elevational view of the same, the opposite side being a mirror image of the side shown;

FIG. 4 is a bottom plan view of the same;

FIG. 5 is a front end view of the same;

FIG. 6 is a rear end view of the same; and

FIG. 7 is an exploded perspective view of the same, the top being in an inverted position and the obscured portion of the bottom being clearly shown in FIG. 1.

I claim:

The ornamental design for a tray for displaying coin holders or the like, substantially as shown and described.
